FUMIGATING APPARATUS

Kenneth Donald Crooks, Chicago, Ill.

Application November 20, 1946, Serial No. 711,133

5 Claims. (Cl. 21—108)

1

This invention relates to fumigating systems and apparatus and particularly to apparatus which may be readily incorporated in building structures, machinery and manufacturing plants for predetermined arrangement in a wide variety of installations.

My system and apparatus while having very wide applicability where fumigation is carried out through the medium of lethal fluids either gaseous or liquid is particularly well adapted for use in factories and mills, such as flour mills, for application to various machinery such as bins, dusters, reels, roller mills, purifiers and the like, wherein a variety of different conditions are present.

At the present time the cost and installation of suitable distributor tube systems in the various machinery of mills and plants is quite high. Most of the distributor tubes are of rigid metal and must be preformed or shaped and then suspended properly to conform to the particular requirements. Uniform distribution of the lethal fluids at the points desired throughout the length of the conduit is difficult to achieve because any orifices formed in metal exude in most instances more fluid than is desired at any one predetermined point.

It is an object of my invention to provide a system and apparatus for lethal fluid fumigating wherein the elements of my apparatus are readily adapted for various positioning and shaping to meet requirements, and wherein the cost of material and installation is greatly reduced compared to apparatus now extensively used.

A further object is the provision of fumigating apparatus of the class described which is adapted to vary uniformly throughout the length of the distributing conduits, discharge the lethal gas or liquid at a predetermined flow rate and so gradually, that optimum conditions are obtained for economical fumigation.

More specifically, it is an object to provide apparatus of the type described wherein the distribution conduits are constructed from flexible liquid-impervious strips of material such as impregnated fabric, and wherein through my discovery and concept, the lethal fluid may be very slowly and uniformly discharged throughout the full length of the conduit.

These and other objects and advantages of the

invention will more fully appear from the following description made in connection with the accompanying drawings, wherein like reference characters refer to the same parts throughout the views and in which:

Figure 1 is a side elevation showing a relatively short fumigant distributor embodying my invention;

Figure 2 is a cross section taken on the line 2—2 of Figure 1;

Figure 3 is a diagrammatic perspective view illustrating the installation of my apparatus in a typical purifier machine in a flour mill;

Figure 4 is a diagrammatic vertical section 15 showing a typical installation in a flour mill mixer; and

Figure 5 is a side elevation of a longer embodiment of my apparatus employing two distributor conduits with a central coupling head.

The cost of lethal fumigating fluids (volatile liquids and gases) is quite high. Apparatus now in extensive use employs metal tubing for use in distribution, such tubing being drilled or otherwise apertured to provide a multiplicity of longitudinally spaced discharge orifices. It is practically impossible to form the apertures in metal of such restricted size that the fluid will emanate slowly enough to provide optimum fumigating conditions. In the case of volatile liquids which

30 vaporize immediately after discharge, the escape, with most commercial apparatus now used, is so rapid that dripping and collection of the liquid before vaporization concentrates the effect and a relatively large amount of the expensive fluid is consumed.

I have discovered after extensive experimentation and research that a very gradual and controlled discharge of lethal fluids may be obtained throughout lengths of fluid impervious conduits 35 through the inherent tubular construction of said conduits by certain stitching methods. The minute holes formed by the sewing machine needles in stitching together impregnated flexible fabric, if properly spaced apart and preferably double 40 stitched, provide at both sides of the conduit produced just the proper arrangement of minute orifices under variable working fluid pressures to give a very gradual, steady and uniform discharge of lethal fluid throughout the lengths of the distributor tubes.

In the simplest form of my invention, as shown in Figures 1 and 2, a short strip of impregnated fabric material such as duck or canvas is longitudinally folded at one side of its longitudinal center line and the doubled strip is doubled stitched, as shown, along the parallel lines A and B forming a hem or tubular conduit 6 in the lower portion thereof and providing an attachment flange or web 7 at the upper portion thereof. On this short distributor conduit of my invention I prefer to bias the upper longitudinal edge of the strip relative to the axis of the conduit 6 so that when the device is supported in substantially horizontal position the point where the lethal fluid is introduced is higher than the outer extremity of the conduit.

The conduit is closed at its outer end in any suitable manner preferably by double stitching transversely thereof on the lines C and D, as shown in Figure 1. In all of the stitching (lines A, B, C and D) a chain stitch is preferred although other types of stitching may be successfully used within the scope of my invention. The intake end of conduit 6 is tightly clamped about the nipple of a suitable coupling such as the L coupling 8 illustrated in Figure 1. The vertical or lower end of this T coupling is readily connected to a source of lethal fluid under pressure. Pressures of from forty to sixty pounds per square inch are suitable and entirely satisfactory for producing excellent results with my apparatus. The stitches may vary from 6 to 16 stitches per inch, depending upon the nature of the fluids to be distributed.

In Figure 5 a double distributor embodying my invention is illustrated comprising a pair of spaced aligned strips of folded and stitched impregnated fabric forming conduits 6 of identical construction with that of the simpler embodiment first described, and leaving marginal upper attachment flanges here shown of uniform width extending the full lengths of the conduit 6. The conduits are closed by stitching at their outer ends and have their adjacent inner ends securely clamped about a pair of nipples 10a extending from a T head coupling 10, the lower end of which is externally screw threaded as shown for ready connection with a source of lethal fluid under pressure.

The flexible and integrally formed attachment flange of my fumigant apparatus lends itself to ready connection with and conformation to various pieces of equipment and supporting structures. Its simplicity and compactness enables it to be readily attached by clips, tacks or other elements to adjust either horizontal or vertical supporting surfaces. In milling machinery and other machines these fabric distributor conduits may be supported horizontally or vertically very close to working parts without interfering with operation of the machines whereby fumigation may be carried out with the machines operated to obtain thorough penetration and optimum conditions.

In Figure 3 the dotted lines indicate the general frame and exterior of a purifier machine used in the milling and manufacture of farinaceous flour. Here it will be noted that an elongated double conduit embodiment of my distributor is attached within the machine adjacent the bottom of the hopper therein. Another single conduit is disposed diagonally below the dome top of the machine. Another (not shown) is attached across the machine at the feed gate.

In Figure 4 an installation which is typical

for enclosed trough conveyors or mixers is illustrated. Here the flanges 7 at the top of the two distributor conduits are secured along supporting walls or to the horizontal bottom of the top 5 of the trough with their conduits 6 suspended thereby and extending horizontally at the top. The tubes, it will be noted, will not interfere with the screw conveyor but extend the full length thereof above the conveyor or mixer.

10 In operation as near as can be detected scientifically the fluid under pressure emanates slowly from the stitching apertures at both or opposite sides of the conduit formed. The escape of such fluid is so gradual and uniform that even where 15 volatile liquids are used no collection or dripping of the liquid occurs but it vaporizes uniformly as it exudes. Much less supply of lethal fluid is required because of the graduated uniform distribution than with all metal or other rigid types 20 of distributor conduits now in use. The distribution is such from opposite sides of the conduit that a very dense and uniform lethal atmosphere is created having higher efficiency for fumigation purposes.

25 It will, of course, be understood that various changes may be made in the form, details, arrangement and proportions of the various parts without departing from the scope of my invention.

30 What I claim is:

1. Fumigating apparatus comprising a tubular conduit constructed from a strip of flexible, substantially fluid-impervious material, the longitudinal edges of said strip being lapped and secured 35 together by a row of narrow stitches extending longitudinally of said strip, said stitches providing a multiplicity of spaced minute orifices for escape of fumigating fluid at a multiplicity of spaced points along said conduit and from both 40 sides thereof, said conduit being closed at at least one of its ends and having a coupling connection for supply of fumigating fluid under pressure.

2. Fumigating apparatus comprising a tubular 45 conduit constructed from a strip of flexible textile material impregnated to an extent to render it substantially fluid-impervious, the longitudinal edges of said strip being lapped, a row of narrow stitches securing said lapped longitudinal edges 50 and said strip together and providing a multiplicity of spaced minute orifices for escape of fumigating fluid at a multiplicity of spaced points along said conduit, means for closing at least one end of said conduit and a coupling connection carried by said conduit at a point removed from its closed end for connection with a source of fumigating fluid under pressure.

3. Fumigating apparatus comprising a tubular conduit constructed from a strip of flexible, substantially fluid-impervious material, the longitudinal edges of said strip lying in side by side relation and a row of narrow stitches extending through said longitudinal edges longitudinally of said strip and securing said edges together to 60 leave a relatively wide longitudinal seam, said stitches providing a multiplicity of spaced minute orifices for escape of fumigating fluid at a multiplicity of spaced points along said conduit, said wide seam constituting a flexible attachment flange for said conduit, means for closing at least one end of said conduit and coupling means for connecting said conduit at a point removed from the closed end thereof with a supply of fumigating fluid under pressure.

4. The structure set forth in claim 3 wherein

said attachment flange formed by said seam tapers from the outer end of said conduit towards said coupling connection to provide for horizontal attachment of said strip with the outer end of said conduit disposed below the level of said coupling.

5. A fumigating unit comprising a central coupling head having a connection element for attachment to a source of fumigating fluid under pressure and having connection elements in communication with said first mentioned connection element and a plurality of tubular conduits, each constructed from a strip of flexible, substantially fluid-impermeable fabric, the longitudinal edges of said strip being lapped and secured together by a row of narrow stitches said stitches providing

10

15

a multiplicity of spaced minute orifices for escape of fumigating fluid at a multiplicity of spaced points along said conduit, each of said conduits being closed at the outer end thereof and having a coupling connection at the opposite end for connection with one of said coupling connections of said coupling head.
